COUPLING ARRANGEMENT FOR AN OSCILLATORY SYSTEM

Carl E. Ellsworth, Anchorage, Ky., assignor to Chemetron Corporation, a corporation of Delaware

Application September 28, 1953, Serial No. 382,525

6 Claims. (Cl. 333—27)

This invention relates to high-frequency oscillator systems such as used, for example, in dielectric heating and more particularly to an inductive-coupling arrangement for reentrant cavity oscillators which affords the wide range of adjustment required to meet the widely different conditions encountered in dielectric heating.

In accordance with the present invention, the coupling arrangement is comprised of a coupling loop having a shorting member or vane pivotally mounted for movement in an arcuate path throughout which opposite sides of the vane are in contact with opposite sides of the loop. Thus, as the vane is moved about its axis, the effective perimeter of the loop is varied so to change either its self-inductance, or the mutual inductance or coupling between the loop and an associated inductive element such as the fin or leg of a reentrant cavity applicator, or to change both the aforementioned self-inductance and the mutual inductance. The pivotal axis of the shorting vane is disposed substantially out of the path of the high circulating currents so that for all positions of the vane substantially all the loop current flows through a portion of the shorting vane which is in contact with the sides of the loop and not through the structure which provides the pivotal mounting for the vane.

More particularly the preferred coupling loop, which is adapted for accommodating high intensities of high-frequency circulating currents, includes at least two wide substantially parallel sides. One dimension of the shorting vane corresponds with the spacing between the sides of the loop, and the other dimension of the vane approximates the length of the loop so to provide engagement of two opposite sides of the vane respectively with the wide sides of the loop throughout the wide range of angular adjustment of the shorting vane.

In another aspect of the present invention the shorting vane is movable to change the self-inductance of the coupling loop while the mutual inductance or coupling between the loop and the associated inductive element is maintained constant.

In yet another aspect of the present invention, the shorting vane is comprised of a plate member which, in shorting out a portion of the coupling loop, effectively shields the shortcircuited portion to minimize inductive interaction between the shorted and non-shorted portions of the coupling loop.

For a more comprehensive understanding of the invention, reference is to be made to the following detailed description taken in conjunction with the accompanying drawings in which:

Fig. 1 is a schematic representation of a high-frequency dielectric heating applicator of the reentrant cavity type embodying the present invention;

Fig. 2 is a perspective view showing in detail the construction of a preferred variable-coupling arrangement;

Fig. 3 is a front elevation view of the variable 70 coupling loop of Fig. 2, with the addition of a device for adjusting the position of the shorting bar;

2

Fig. 4 is an enlarged perspective of a preferred form of the shorting vane or bar;

Fig. 5 is a sectional view of the shorting vane taken along a line substantially corresponding to line 5—5 of Fig. 4;

Fig. 6 is a perspective view of a portion of one type of coupling loop embodying the present invention for varying the self-inductance of the loop without substantial change in mutual inductance or coupling between the loop and an associated inductive element; and

Fig. 7 is a perspective view of a coupling loop embodying the present invention in which the axis of rotation of the shorting vane is parallel with the flux lines linking the loop.

Referring to Fig. 1, there is illustrated in schematic form a coupling loop 10 embodied in a dielectric heating applicator 11 of the reentrant cavity type generically similar to that described and claimed in Warren application Serial Number 138,628, filed January 14, 1950, abandoned in favor of Warren application Serial No. 419,633, filed March 26, 1954, now Patent No. 2,783,344. In the particular embodiment illustrated, the applicator 11 is comprised of a metallic housing 12 within which the dielectric work to be treated is disposed for heating by the high-frequency electric field established between an upper electrode 13 and a lower electrode 14 which may be the lower wall of housing 12, a raised platform, or in some instances a conveyor. The upper electrode 13 is connected to the lower free end of the metallic inductor or fin 15 whose upper end is connected to the top wall of the housing 12. Usually, flexible conductors are included in the fin-electrode assembly 13, 15, as between electrode 13 and the adjacent end of the fin 15, or as shown between the top wall of the housing 12 and the adjacent end of the fin 15 to permit raising and lowering of the upper electrode 13. The inductance of fin 15 provides the lumped inductance of a heating circuit resonated by the capacity between the heating electrodes. The high-intensity, high-frequency magnetic field of fin inductor 15 traverses the coupling loop 10. The current return path between the upper end of the fin 15 and the lower electrode 14 is provided by the wall structure of the housing 12 and is of negligible impedance. The resonator thus formed is inductively coupled by loop 10 to the anode of an oscillator tube (not shown) to provide an oscillator system generically similar to those disclosed and claimed in the aforesaid Warren applications.

In dielectric heating applicators, variations in electrical and/or physical characteristics of the load occur during a heating cycle. Such variations in load change the operating characteristics of the applicator and may result in damage to the load, overloading of the dielectric heating unit, damage to one or more components such as the oscillator tube, or lowering of the heating rate. It usually is necessary or desirable, therefore, to make compensatory changes of proper sense and magnitude to off-set the effect of such changes of the load characteristics to reestablish desired operating conditions in the applicator.

In general, such compensatory change may be effected by changing the mutual inductance or coupling between the loop 10 and the inductor or box-like fin 15, or by changing the self-inductance of the loop, which latter changes the natural frequency of the loop, or by changing both the aforementioned mutual inductance and the self-inductance. Various compensating arrangements for varying one or more of such parameters are disclosed and claimed in the aforesaid Warren application and in Warren applications Serial Nos. 419,072, 419,073 and 419,074, all filed March 26, 1954, now respectively Patents Nos. 2,783,346, 2,783,345 and 2,783,347, and in co-

pending applications, Carl E. Ellsworth, Serial Number 263,599, filed December 27, 1951, now Patent No. 2,712,050, and Thomas L. Wilson, Serial Number 302,721, filed August 5, 1952, now Patent No. 2,684,433.

The effective perimeter and area of the coupling loop 10 may be varied by a shorting plate member or vane 20 which is pivotally mounted at one end thereof on the coupling loop by way of shaft 21. The vane 20 is arcuately movable about the axis of the shaft 21 which is transverse to opposite sides 22 and 23 of the loop. The shorting vane 20, formed of conductive material, such as copper or aluminum, is in slidable electrical contact with the opposite sides 22 and 23 of the loop and functions as a short-circuiting device between the sides.

In the particular loop construction shown in Fig. 1, the copper pipes 16, 17 for supplying coolant to the anode of the oscillator tube (not shown) serve as a form for the electrically conductive sheet 18. Ends 16A, 17A of the pipes, electrically connected to wall 12A of the applicator housing, serve as a ground connection for one end of the loop. The other ends 16B, 17B of the pipes pass through insulators 19 in housing wall 12A for connecting the other end of loop 10 to the anode of the oscillator tube. When as shown in Fig. 1, the loop sheet 18 is on the outside of the loop form provided by pipes 16, 17, there are preferably added, as discussed in connection with Fig. 2, supplemental sheets connected to the inside of the loop form for contact by opposite sides of vane 20.

As the vane 20 of Fig. 1 is moved about its pivotal axis and within the perimeter of the loop 10, the percentage of the electromagnetic field linked by the loop is varied so to change the coupling between the loop and the inductor 15. With the vane 20 in its horizontal position (Fig. 1), preferably as close to the top of the loop 10 as possible, the effective area of the loop is maximum and linkage by the loop of the flux produced by current in the inductor 15 is a maximum. As the vane 20 is moved progressively downwardly, as illustrated by dotted lines, toward an ultimate vertical position, the linkage decreases to a minimum value due to more and more of the area of the loop 10 being shorted out. The decrease in percentage of flux linked by the loop will cause a decrease in the mutual inductance or coupling. At the same time, as the vane 20 is moved downwardly the effective length of the loop is decreased, which decreases the self-inductance of the loop and raises its natural frequency. When operating in the supra optimum coupling range, both the decrease in coupling and the increase in natural resonant frequency of the loop have the effect of increasing electrode voltage. For an explanation of supra optimum coupling, reference may be had to the aforementioned Warren and Wilson applications.

The shape and dimensions of the shorting vane 20 are determined by the internal configuration of the loop 10 and the range of coupling desired. More specifically one of the dimensions of the vane 20 is such as to provide for engagement between two opposite sides of the vane and the sides 22 and 23 of the loop 10 throughout the range of arcuate adjustment of the vane. For the maximum range the vane 20 should have a dimension, normal to its pivotal mounting, substantially equal to the distance between the upper and lower portions of the loop, i. e. the length of the loop.

Inductive interaction or coupling between the shorted and unshorted portions of loop 10, and between the shorted portion of the loop and inductor 15 is minimized by providing, as in Fig. 1, that the shorting vane 20 shall shield the shorted portion of the loop from linkage with the electromagnetic fields of the unshorted portion of the loop and of the inductor. Accordingly, the preferred embodiments of the present invention afford a greater range of electrode voltage variation than heretofore attained with coupling loops of the fixed type having shorting arrangements which do not shield the shorted portion of the loop. In these other types of shorting arrangements,

as shown and claimed in said Warren applications, there is present an inductive interaction between the shorted and unshorted portions of the coupling loop. This is analogous to the interaction between shorted and unshorted turns of a coil which, as is well known, will cause the overall inductance of the coil to decrease due to the field produced by the current in the shorted turn being out of phase with the field produced by the unshorted portion of the coil. Such decrease in inductance will operate with the decreased coupling between the unshorted portion of the loop and the fin inductor so as to increase the range of variation of the electrode voltage. However, without the shielding effect afforded by the preferred embodiments of the present invention, the shorted portion of the coupling loop will also be subject to linkage by the electromagnetic field of the fin inductor, and as the perimeter of the unshielded shorted portion increases, the coupling between that portion and the fin structure would increase accordingly. This latter may be of greater effect upon electrode voltage than the effect of the decrease in inductance of the loop caused by the interaction between the unshielded shorted and unshorted portions of the coupling loop. Hence the range of electrode-voltage variation with previous unshielded shorting arrangements is less than that obtainable with the shielded, shorting arrangement of the preferred embodiments of the present invention.

The improved operation afforded by the shielding effect above described is accomplished in the embodiment of Fig. 1 by contact of two opposite sides of the shorting vane 20 respectively with the opposite sides of the loop 10 throughout the range of adjustment of the vane, so as to eliminate spaces between the sides of the shorted portion of the loop through which the electromagnetic field of the inductor 15 could pass to link with the shorted portion of the loop.

Movement of the shorting vane 20 about its pivotal axis may be effected by any well known device. As exemplary of such a device, there is illustrated (Fig. 1) an external manually operable crank 24 mounted on an end of the shaft 21 which extends through the wall 12A of the housing 12. At least a portion of the shaft 21 should be of insulating material to insulate the crank or knob 24 from the high potential of the loop 10.

In Fig. 2 there is shown in detail a commercial type of variable coupling loop arrangement embodying the present invention. As in Fig. 1, loop 10 is comprised of a framework consisting of a pair of spaced copper pipes 16 and 17 preferably conductively connected by a sheet 18 of material such as copper or the like (for clarity not shown here but similar to the sheet or web 18 shown in Fig. 1) which substantially covers the outer periphery of the pipes to form the single coil loop.

Particularly in those instances where the opposite sides 22 and 23 of the coupling loop 10 are of different widths, or are of curved configuration, or contain structural ribs or the like, spaced parallel electrically conductive plates 25 and 26 may be added to provide flat parallel sides for more effective contact with opposite sides of shorting vane 20A. The plates 25 and 26 may be of aluminum or like material and mounted in any well known manner respectively on opposite sides 22 and 23 of the coupling loop 10. In Fig. 3 the plate 26 is omitted for clarity. In providing flat parallel sides, the plates 25 and 26 also present a greater area for contact between the shorting vane 20A and the coupling loop 10 throughout the range of movement of the vane to thereby increase the range of variation in mutual inductance and self-inductance of the loop. The shorting vane 20A, Fig. 2, is mounted for arcuate movement within the area defined by the spaced parallel plates 25 and 26 by means for the shaft 21 journaled in bearings 21A secured on ends of the plates.

In order to provide improved electrical contact throughout the arcuate movement of the shorting vane 20A, a plurality of resilient contacts 27, Figs. 2-4, may be se-

cured on opposite sides of the vane for engagement with the spaced parallel plates 25 and 26 of the coupling loop. Substantially all of the high circulating currents which flow from the loop 10 into the shorting vane 20A will be carried by the resilient contacts 27 of the shorting vane. Most of the current intercepted by the shorting vane 20A will pass through the vane contacts 27 furthest away from the shaft 21 of the shorting vane 20A and, accordingly, at most only a very small portion of the total circulating current will be conducted by the shaft. This construction obviates the possibility of excessive heating, or even welding, at high resistance points in the shaft structure, such as bearings 21A, etc., which might cause the shaft 21 to bind or freeze.

The shorting vane or plate member 20A is shown in detail in Figs. 4 and 5 to be comprised of a framework including spaced longitudinal members 30 and laterally spaced reinforcing struts 31, the whole covered by a skin 32 of thin sheet metal. The shaft 21 passes through the vane 20A at one side thereof and is firmly affixed thereto. Contact between the shorting vane 20A and the inner sides of the spaced parallel plates 25 and 26 is assured throughout the range of arcuate sliding movement of the shorting vane by the plurality of resilient loop contacts 27 formed of beryllium-copper straps mounted along the two opposite sides of the vane which extend normal to the pivoted side of the vane. The contacts 27 may be mounted on the shorting vane framework by means of screws or in any other well known manner. In the embodiment shown, the shorting vane 20A is rectangular in configuration, complementary to an outline defined by the spaced parallel plates 25 and 26. In embodiments in which the spaced plates are not parallel, the contacts 27 may be varied in length to conform to the particular configuration, and when the variation is from the top of the plates to the bottom the resilient contacts will deform in accordance with the variation.

For rotation of the shaft 21 of the shorting vane 20A, there is provided a shaft 33 (Figs. 2 and 3) which passes through wall 12A of the housing and which is connected internally thereof to shaft 21 by an insulated coupling 34. The coupling 34 should have an effective length sufficient to insulate the end of shaft 33 from the high voltages of the coupling loop. In many embodiments, where the invention is applied to dielectric heaters of the type illustrated, the longitudinal length of an insulator is limited by the distance of the coupling loop from the adjacent wall of the applicator housing. To provide the adequate insulation necessary to permit connection of a driving means to shaft 33 at ground potential, the insulated coupling 34 comprises a large sheet of insulating material 35 having mounted on opposite sides thereof pairs of metallic stand-off connectors 36 and 37. The connectors 36 and 37 are respectively connected by metal bars 38 and 39, displaced at right angles to one another, and to which the shafts 21 and 33 are respectively connected. The effective insulation length of this construction is equivalent to a bar of insulating material several times the distance between connecting bars 38 and 39.

The driving means for the shorting vane 20A (Fig. 3) is located exteriorly of housing 12 and is comprised of a reversible motor 40 whose motion is transmitted to the shorting vane 20A by way of sprocket and chain drive 41, shaft 42, sprocket and chain drive 43, gear-reduction box 44, shaft 33, insulated coupling 34 and shaft 21 (Fig. 2). The driving means illustrated is merely exemplary of a single suitable type.

Stops may be provided to fix the limits of movement of the shorting vane 20A. Specifically, the shaft 42 may be provided with a traveling nut mechanism 45 including limit-switch operating cams 46 and 47. The cams 46 and 47 are mounted on traveling nut 45A by means of thumb screws 46A and 47A respectively. The deenergization of motor 40 at predetermined limits of travel of shorting

vane 20A is controlled by switches 50 and 51, which may be of the microswitch type. The switch 50 includes a member 50A engageable by a forward inclined surface of cam 47 to open the power circuit of motor 40 and halt the upward travel of the shorting vane 20A. The lower limit of travel of the shorting vane 20A is controlled by micro-switch 51 whose member 51A is operated by a forward inclined surface of cam 46. The switch operating cams 46 and 47 may be adjusted so as to vary the upper and lower limits of travel of the shorting vane. To this end the cams 46 and 47 are slotted and made adjustable relative to their respective thumb screws 46A and 47A. The travel of nut 45A may be further limited by fixed mechanical stops (not shown) just beyond the range of adjustment of the limit switch cams.

In the modification shown in Fig. 6, coupling loop 10B is comprised of two sections one of which has an area 60 threaded by magnetic flux moving in a direction indicated by the arrows and the other of which has an area 61 which is so oriented that it is not threaded by any appreciable amount of the magnetic flux. The horizontal portion of the coupling loop 10B is provided with a pair of spaced parallel vertically disposed plates 25B and 26B serving functions similar to that of the plates 25 and 26 of Fig. 2. The shorting vane 20B, similar to vane 20 of Fig. 1, is in slidable contact with the spaced parallel plates along the entire coextensive portions thereof.

Resilient contacts, not shown, but similar to contacts 27 of Fig. 2 may be added to the sides of the vane 20B for improved electrical contact between the plates 25B and 26B and the vane.

Movement of the shorting vane 20B about the axis of shaft 21B will vary the inductance of the coupling loop 10B and hence change the natural frequency of the loop. Inasmuch as the area 61 of the coupling loop 10B is not linked by the magnetic flux, movement of the vane 20B will not appreciably change the coupling between the loop and an associated inductor (not shown). However, change in the natural frequency of the coupling loop 10B will effect a change in the electrode voltage in manner described in the aforesaid Wilson application and therefore the arrangement provides compensation of substantial range for changes in load characteristics.

Movement of the shorting vane 20B about its axis may be effected by any well known device. For illustrative purposes there is disclosed a manual driving device similar to that illustrated in Fig. 1 wherein a crank 24B is mounted on the shaft 21B.

In Fig. 7 there is illustrated another modification of the present invention wherein a coupling loop arrangement includes a shorting vane 20C having only one side in slidable electrical contact with a side of a coupling loop 10C. The shorting vane is pivotally mounted on a side 22C of the loop 10C by means of a shaft 21C extending parallel with the lines of flux moving in a direction indicated by arrows. The mutual inductance between the coupling loop 10C and an inductor similar to inductor 15 of Fig. 1 is varied through movement of shorting vane 20C from an upper vertical position where the self-inductance of the loop, the mutual inductance and coupling of the loop and inductor are at a maximum, to a lower vertical position where the aforesaid self-inductance, mutual inductance and coupling are at a minimum.

The coupling loop 10C may be rectangular in configuration similar to that shown in Fig. 1. However, as illustrated side 23C of the coupling loop is of arcuate configuration to enhance the range of variation of self-inductance and mutual inductance by permitting rotation or pivotal movement of the shorting vane through an arc of approximately 180°.

Good electrical contact between the vane 20C and the loop 10C is assured by the provision of plate 25C mounted on side 23C of the loop and the addition of resilient contacts 27C on the adjacent side of the shorting vane. The plate 25C may extend completely around

the inside of the loop 10C in much the same manner and for the same purpose as sheet 18 which covers the outside of the loop 10 (Fig. 1).

Movement of the shorting vane 20C may be effected by way of a crank 24C mounted exteriorly of the applicator housing and mechanically connected to the shorting vane 20C through shaft 33C, bevel gears 62, 63 and shaft 21C. A portion of one of the shafts 33C, 21C, like shaft 21 (Fig. 1), is made of insulating material to maintain the crank 24C at ground potential.

Passage through the shaft structure 21C of high-frequency, high-intensity currents which circulate in the loop is avoided by a distribution of such currents through a plurality of resilient conductive straps 64 fastened to upper and lower surfaces of the shorting vane and the side 22C of the coupling loop. The straps 64 serve as short-circuiting members permitting the currents to by-pass the shaft structure. In this modification, the shorting vane does not shield the shorted portion of the loop.

While there have been described various embodiments of this invention, it will be understood that further modifications may be made without departing from the spirit and scope of the invention as set forth in the appended claims.

What is claimed is:

1. In an adjustable coupling arrangement for a high-frequency oscillator, the combination of a single turn coupling loop having substantial width and length, said loop having a substantial portion of at least two sides formed of conductive sheet metal, means for varying the effective coupling area of said loop by moving lengthwise of said loop an electrical connection extending from one sheet metal side of said loop at a location adjacent one end of said loop to the other sheet metal side thereof to move progressively along and lengthwise of at least one side of said loop the current path between opposite sides thereof, said means comprising a shorting plate member which extends across said width of said loop, and the edge-portions thereof forming said electrical connection from said one sheet metal side of said loop to said other sheet metal side thereof, and means pivotally mounting said shorting plate member at one end thereof for rotation of said shorting member within and relative to said loop from said position close to said one end through

an arcuate travel path for moving said electrical connection to shorten said current path.

2. The adjustable coupling arrangement of claim 1 in which one side of said loop has an arcuate configuration and in which said shorting plate member is pivoted about an axis parallel with the axis of the arcuate portion of said loop with the opposite end of said shorting member movable along the arcuate portion of said loop from a position adjacent one end of the loop toward the opposite end of the loop to vary the effective perimeter length of said loop.

3. The coupling arrangement of claim 1 in which the axis of rotation of said shorting plate member is normal to the planes which respectively include the sheet metal forming the respective sides of said loop.

4. The adjustable coupling arrangement of claim 3 in which said pivotal mounting means is carried by said loop and in which said shorting plate member has a length which taken normal to the axis of its mounting means is approximately equal to said length of said loop.

5. The coupling arrangement of claim 1 in which the portion of said loop including said conductive sheet metal is disposed at right angles to the plane of the remaining portion of said loop, said pivotal mounting means being located adjacent one end of said loop for rotation of said shorting plate member between the sheet metal portions thereof, whereby the inductance of said loop may be varied by rotating said shorting plate member to change the length of said loop without variation of flux passing through said remaining portion of said loop.

6. The adjustable coupling arrangement of claim 1 in which said shorting plate member comprises spaced walls of thin sheet metal reinforced by spacing struts and having along opposite edges thereof a plurality of resilient loop contacts, which loop contacts engage said thin sheet metal to form said electrical connection between said sheet metal sides.
